UNITED STATES PATENT OFFICE.

DANIEL MCFARLAN MOORE, OF EAST ORANGE, NEW JERSEY, ASSIGNOR TO GENERAL ELECTRIC COMPANY, A CORPORATION OF NEW YORK.

ELECTRIC DISCHARGE DEVICE.

Application filed March 5, 1921. Serial No. 449,700.

The present invention relates to electric discharges between electrodes in gases and its main object is to provide a simple direct method and apparatus for starting an arc between electrodes in an enclosed space. Prior to my invention it was found necessary to provide enclosed arc devices with special starting mechanism, such, for example, as high potentials, electrode heating circuits, ionizing devices within the bulb, or the like, which usually required auxiliary electromagnetic switches, cutouts and the like.

In accordance with my invention, electric arc devices, for example, lamps, rectifiers, or the like, are provided in which an arc may be started by the simple connection to a source of electric current. Devices embodying my invention preferably are provided with a filling of a highly conductive gas, such as helium or neon, in which a glow discharge may be produced at a moderate voltage, that is, gas of low dielectric strength. These and other aspects and advantages of my invention will be more fully explained in the following specification taken in connection with the accompanying drawing in which Fig. 1 shows somewhat diagrammatically a lamp embodying my invention; Fig. 2 illustrates a rectifier constructed in accordance with my invention; Figs. 3 and 4 illustrate modified circuit connections which may be used with devices embodying my invention, and Figs. 5 and 6 illustrate modified electrode structures.

The novel features of my invention will be pointed out with particularity in the appended claims.

The lamp illustrated by Fig. 1 comprises a bulb 6 shaped much like the usual incandescent lamp and containing electrodes 7, 8, carried by the ends of supports 9, 10, which are sealed into a stem 11. The electrodes 7, 8, consist of refractory metal, preferably tungsten, and are constituted by a filament closely wound in the form of a helix. It is not essential that the electrodes should assume this particular form which is shown in Fig. 1 merely to illustrate one specific embodiment of my invention. In general, the electrodes should have such shape and mass that they are readily heated to incandescence, as herein-after more fully described.

In the particular form of lamp shown in

Fig. 1, the electrodes may consist of tungsten wire having a diameter of .010 closely wound in a helix of about 15 turns on a mandrel of about .035 diameter. The gap between the electrodes 7, 8, may be about ⁶⁰ $\frac{1}{8}$ of an inch. The electrode supports 9 and 10 may consist of tungsten of about .060" diameter. They are sealed into the bulb 6 in any well understood manner, for example, these wires 9, 10 may be connected to special sealed-in conductors consisting of nickel-iron alloy and coated with copper, as now well known in the incandescent lamp art. The bulb 6 is filled with a suitable atmosphere which preferably consists of ⁷⁰ neon, helium, or a gaseous mixture containing neon or helium, although other gases such as argon or nitrogen may also be used. I prefer to use a gaseous filling consisting of a monatomic gas, such as neon, or neon ⁷⁵ with an admixture of about 20% helium, which is introduced after the bulb has been well exhausted and freed from water vapor according to methods now well understood. I prefer to use a pressure of about 65 millimeters of mercury altho the pressure within the bulb may be varied within wide limits, depending upon the character of the electrodes and the nature of the discharge which is desired.

Supply conductors 12, 13, connecting the terminals of the lamp to a suitable source of alternating or direct current, as represented by the mains 14, contain a series resistance 15, and a switch 16. When the mains 14 supply direct current, say, at about 220 volts, the series resistance 15 should represent about 280 ohms. Upon closing the switch 16 there first appears surrounding the electrodes 7, 8, an electric glow or corona discharge of light having the characteristic neon color with a current of about .15 amperes flowing in the circuit. The amperage of the current steadily increases until at about .30 amperes the diffuse corona has disappeared and the electrodes become centers of spheres of intense whitish colored light. At this stage the electrodes are heated above redness, the current continues to rise and the electrodes become more highly heated. At about .50 amperes the spheres of light surrounding the electrodes 7, 8, lose their prominence and a very intense white arc appears in the gap between the electrodes. This arc continues to operate in ⁹⁵ ¹⁰⁰ ¹⁰⁵ ¹¹⁰

definitely at a voltage consumption between the terminals of the lamp of about 60 volts, the remainder of the voltage being consumed in the resistance 15. When alternating current is supplied by the mains 14, as in Figs. 3 and 4, there is preferably provided a regulating device in circuit with the lamp which will automatically provide for a reduction of voltage as the current increases 10 without an appreciable consumption of energy. For example, in Fig. 3, I have provided a reactance device having a winding 15 in series with the lamp on a magnetic core 16. As the amperes coming through 15 the lamp increase the voltage drop across the terminals of the reactance windings 15 increases.

The arc device shown in Fig. 4 is connected to the secondary winding 18 of a 20 transformer, the primary winding 19 of which is supplied from mains 14. The core 20 of the transformer is designed to have a relatively large leakage flux, the transformer being in general so designed that the open 25 circuit voltage is materially higher than the operating voltage. This transformer efficiently reduces the voltage impressed upon the electrodes 7, 8, with little loss of energy as the current flowing through them increases.

In Fig. 2 I have shown a rectifier embodying my invention in which the cathode 22, consists of a helically wound tungsten wire of relatively small mass, both terminals of 30 which are connected to a supporting wire 23 sealed into the wall of the envelop 6 in the usual manner. The anode 24 has a mass and heat dissipating capacity sufficiently great to operate at a temperature too low 35 to act as a seat of an arc. When the switch 16 is closed a glow discharge occurs between electrodes 22 and 24 which causes the cathode 22 to be heated to incandescence, as already described in connection with Fig. 1. As the 40 current increases the voltage is automatically lowered by the inductance device 25, which has been diagrammatically shown as a simple coil, which may have any suitable form. The arc between electrodes 22 and 24 is 45 maintained by the half waves of current which have a negative polarity with respect to the electrode 22. The heat generated by the discharge through the gaseous filling in the bulb 6 may be utilized to produce mercury vapor from the mass of mercury 26. As 50 the heavy mercury vapor in the device shown in Fig. 2 displaces the filling of neon or other suitable gas into the upper part of the bulb 6, the arc continues to operate in 55 the mercury vapor.

Although I have shown in Figs. 1, 2, 3 and 4, only helical electrodes embodying my invention, I wish it to be understood that

the form of these electrodes may be varied without departing from my invention; for 60 example, in Fig. 6 I have shown a form of electrode in which the heat from a helix 7 aids a larger mass of tungsten 8 to become heated, and Fig. 5 shows an electrode consisting of four adjacent helices, the free ends 70 28 of which are twisted together and joined to a supporting wire 29. These helices may consist for example, of 15 turns of closely wound .010 tungsten wire wound upon a mandrel .035 in diameter. Other variations 75 can be made but less starting voltages will be required when the electrodes are provided with cavities or their equivalent.

What I claim as new and desire to secure by Letters Patent of the United States, is:—

1. The method of starting an electric arc discharge in a gas between closely adjacent electrodes constituted of conducting material one of which comprises a body of closely adjacent conductors of small section to facilitate the production of corona which consists in initially impressing upon said electrodes a potential sufficient to produce a glow discharge therebetween, maintaining such glow discharge to bring said small conductors to incandescence and increasing the current flowing between the electrodes.

2. An electric arc device comprising a sealed receptacle containing a gas having moderate voltage breakdown characteristics, 85 refractory metallic electrodes supported in said receptacle adjacent each other with a relatively short discharge path therebetween, one of said electrodes comprising a body of closely adjacent conductors of small section to facilitate the production of a glow discharge 90 between said electrodes at relatively low potential difference therebetween, and circuit connections to said electrodes arranged so that each electrode carries current 100 and only such current as flows between said electrodes during the starting of a discharge between said electrodes.

3. An electric arc device comprising a sealed receptacle containing a gas having 110 moderate voltage breakdown characteristics, electrodes supported in said receptacle adjacent each other with a relatively short discharge path therebetween, one of said electrodes comprising a body of closely adjacent 115 filamentary conductors of small section to facilitate the production of a glow discharge between said electrodes at relatively low potential difference therebetween, said receptacle being provided with a single pair of 120 circuit terminals connected respectively to said electrodes.

In witness whereof, I have hereunto set my hand this 3d day of March, 1921.

DANIEL McFARLAN MOORE.
